UNITED STATES PATENT OFFICE.

GEORGE R. OSBORN, OF NEW YORK, N. Y.

DESIGN FOR AN EASEL.

SPECIFICATION forming part of Design No. 16,333, dated October 13, 1885.

Application filed August 5, 1885. Serial No. 173,658. Term of patent 7 years.

To all whom it may concern:

Be it known that I, GEORGE R. OSBORN, a citizen of the United States, residing at New York, in the county of New York and State 5 of New York, have invented and produced a new and original Design for Easels; and I do declare the following to be a full, clear, and exact description of the same, reference being had to the accompanying drawing, forming a part thereof.

The leading novel feature of my design for easels consists of scroll-guards on the outer ends of the rests for the picture.

As clearly represented in the accompanying 15 drawing, the pins or rests A A of the easel terminate at their outer ends in scroll-guards

B B. The scrolls are connected at their outer ends, and are ornamented on the surface to correspond with the ornamented surface of the arched back of the easel. The connection 20 of the ends of the scroll-guards is not a necessary part of my design.

I claim—

The design for an easel herein shown and described, the same consisting of an easel having scroll-guards. 25

In testimony whereof I affix my signature in presence of two witnesses.

GEORGE R. OSBORN.

Witnesses:

JAMES H. LAMPHEAR,
JOHN L. PEQUE.
